UNITED STATES PATENT OFFICE.

EINAR EDQUIST, OF CHICAGO, ILLINOIS.

VACUUM BOTTLE.

Application filed May 11, 1928. Serial No. 276,936.

This invention relates to improvements in vacuum bottles and its chief object is to provide a vacuum bottle provided with clamping means whereby a cup may be removably secured as a cap or cover to the top of the bottle.

With the foregoing and other objects in view the invention consists in the combination and arrangement of parts to be herein-
10 after fully described, pointed out in the claims and illustrated in the accompanying drawing which forms a part of this applica-
tion for patent and in which—

Fig. 1 is a fragmentary view of a vacuum
15 bottle constructed according to the present
invention and provided with a cup.

Fig. 2 is a vertical sectional view taken on
line 2—2 of Fig. 1.

Fig. 3 is a plan view of Fig. 2 with the
20 cup in an altered position.

Fig. 4 is an enlarged fragmentary view of
Fig. 3 illustrating the clamp lever employed.

Like reference characters denote corre-
25 sponding parts throughout the several views.
The present vacuum bottle is so constructed
that it may releasably carry a porcelain cup
which when secured to the bottle serves as a
cap therefor and when detached serves as a
30 drinking cup. It is recognized that the porce-
lain cup has many advantages over metal
cups, paper cups and the like as it is a poor
conductor of heat, it is easy to clean and keep
clean and is therefore sanitary and convenient
35 in use.

The present invention provides a vacuum
bottle having a resilient collar adapted to
releasably grip the mouth of the porcelain
cup when the cup is inverted, and a handle-
40 receiving bracket for the cup handle that
operates to hold the cup in position as a bottle
cap.

The envelope 1 of the vacuum bottle is
formed with an integral collar 2 that is spaced
away from the neck 3 of the bottle to form
45 a channel 4 that extends from a straight
shoulder 5 around the bottle. The said col-
lar 2 forms one wall, the outer wall, of the
channel 4 for approximately one-half the cir-
50 cumference of the bottle or to a point di-
ametrically opposite the shoulder 5 and from
this point 6 the collar 2 is separate from the
envelope 1 as clearly shown in Fig. 3.

That part of the collar 2 between the shoul-
55 der 5 and the point 6 is substantially nar-
rower than that portion between the point 6
and the loose end of the collar, the collar

being inwardly curved along its upper edge.
Pivotal secured to the lug 7 carried by the
collar 2 is the bracket 8 that is connected by
the locking lever 9 to the link 10 that is car-
ried by the bracket 11 carried by the free end
60 of the collar 2. The locking lever is some-
what on the order of a toggle lever and when
its free outer end, forming a finger piece, is
moved toward the bracket 11 it loosens the
connections between the brackets 8, 11, as
65 shown in Fig. 3, thus permitting one portion
of the collar 2 to move away from the en-
velope 1. When the lever 9 is moved toward
and against the bracket 8 the bracket con-
nections are stretched and the movable por-
70 tion of the collar 2 moved into frictional en-
gagement with the envelope and with the
fixed end of the collar 2.

To the collar 2 at the point 6 a handle
75 bracket 12 is secured. It is of the general out-
line and shape, though slightly larger, than
the handle 13 of the porcelain cup 14 which it
is adapted to receive releasably and to house
as shown in Fig. 1, said handle bracket being
80 formed with a vertical stop bar 15 which pre-
vents movement laterally or outwardly of the
cup handle 13 from the bracket 12.

In Fig. 3 the collar 2 and clamping device
85 8, 9, 10, 11 are shown open and the porcelain
cup in inverted position has been applied so
that the mouth of the cup is received in the
channel 4.

The cup is now oscillated in the said chan-
nel until the handle 13 is moved into the
90 handle bracket. The lever 9 is now moved
to tighten the clamping means thus binding
the free portion of the collar 2 against the
mouth of the cup as shown in Fig. 1. The
cup is now securely locked to the bottle. To
95 remove the cup the lever 9 is moved to open
position and the cup oscillated to withdraw
the handle 13 from the bracket 12.

What is claimed is:—

1. In a vacuum bottle, an envelope formed
100 with a channel at its junction with the bottle
neck, a collar integral with said envelope but
detached therefrom throughout a portion of
its length, a locking lever connecting the ends
105 of said collar whereby the detached end may
be releasably clamped against the attached
end of said member, and a cup handle bracket
carried by said collar.

2. In a vacuum bottle, an envelope formed
110 with a channel at its junction with the bottle
neck, a collar integral with said envelope but
detached therefrom throughout a portion of

its length, said collar, in one position, forming one wall of said channel, a locking lever connecting the ends of said collar whereby the detached end may be releasably clamped 5 against the attached end thereof, and a cup handle bracket carried by said collar.

3. In a vacuum bottle, an envelope formed with a cup receiving channel at its junction with the bottle neck, a collar integral with 10 said envelope but detached therefrom throughout a portion of its length, a locking lever for said collar, a handle bracket carried by said collar, and a stop bar for said handle bracket.

15 4. In a vacuum bottle, an envelope formed

with a channel at its junction with the bottle neck, a collar integral with said envelope but detached therefrom throughout a portion of its length, the attached portion of said collar being narrower than the detached portion, 20 said collar being inwardly curved along its top edge, a locking lever connecting the ends of said collar whereby the detached end may be releasably clamped against the attached end and against said envelope, and a cup 25 handle bracket carried by said collar.

In testimony that I claim the foregoing as my own I have hereto affixed my signature.

EINAR EDQUIST.
